[57] CLAIM

The ornamental design for coin counter, as shown and described.

DESCRIPTION

FIG. 1 is a top plan view of the coin counter showing my new design;

FIG. 2 is a side elevational view thereof, the opposite side being a mirror image of the side shown;

FIG. 3 is a bottom plan view thereof;

FIG. 4 is a left end elevational view thereof; and

FIG. 5 is a right end elevational view thereof.
